UNITED STATES PATENT OFFICE.

FRANK E. WELLMAN, OF KANSAS CITY, KANSAS, ASSIGNOR TO THE KANSAS CITY GASOLINE COMPANY, OF KANSAS CITY, KANSAS, A CORPORATION OF KANSAS.

METHOD OF REFINING LIQUID HYDROCARBONS.

1,390,002.

Specification of Letters Patent. Patented Sept. 6, 1921.

Application filed November 27, 1917. Serial No. 204,228.

To all whom it may concern:

Be it known that I, FRANK E. WELLMAN, a citizen of the United States, residing at Kansas City, Kansas, have invented certain new and useful Improvements in Methods of Refining Liquid Hydrocarbons, of which the following is a specification, reference being had therein to the accompanying drawing.

My invention relates to the art of refining liquid hydrocarbons, and more particularly to a process of and apparatus for refining hydrocarbons in totality and in the liquid stage, that is, treating the entire body of a mixture of hydrocarbons of different gravities and boiling points as distinguished from the method of first distilling to remove the lighter hydrocarbons sequentially and cracking only the heavier ones.

Other objects of the invention will be apparent from a perusal of the following specification and drawings.

My invention is illustrated in the accompanying drawing which is a diagrammatic view showing the system laid out in a series of apparatus elements constituting a complete circuit, portions of the apparatus being shown in section.

Referring to the drawing, 1 represents a containing vessel for the hydrocarbon to be refined, fitted with means for initial charging as pipe 1^a and valve 1^b and also with means for return charging such as pipe 48 in a manner which will be presently described. The container 1 performs the function of a boiler or primary vaporizer, is fitted with gages 5 and 6, and suitably mounted in brick or other housing 3, constituting a furnace with fire box 2, back draft or flue 2^a, and stack 4. The boiler 40 may be heated in any suitable manner, but in practice I use oil or gas, injected into the fire box through the nozzle 67 and controlled by the valve 66, from which in the present case the pipe line 65 extends back 45 to the receiving drum or tank 61, conveying therefrom to the furnace non-condensable gases which have been passed through the condenser system. Hydrocarbon vapor is generated in the boiler 1 under low pressure, at the normal boiling point of the liquid. From the upper part of the boiler 50 an outlet pipe 7 extends to a T-joint 8, from which a straight pipe line 11 leads to the condenser, and a branch pipe 10 with a controlling valve 9 extends to any suitable re-

ceiving apparatus. Pipe 10, with its valve 9, are to take off the so-called "natural run" of gasoline.

The coil of the condenser 12, discharges through pipe 13 into a receiving tank 14. 60 The condensate deposited in the receiving tank 14, which is not homogeneous but composed of various cracked and uncracked fractions of the original oil, is drawn from the receiving tank through the suction pipe 65 15 of the pump which discharges under high pressure through the discharge conduit 17 containing a check valve 19 and communicating with a pressure gage 18 at a point between the check valve and the pump. 70 The conduit 17 connects through a T-joint 75 with the conduit 20 leading to the superheater or retort 23. The conduit 17 is also connected through the T-joint 75 to the pipe 80 upon which is mounted a safety valve 81 75 having its discharge end connected through pipe 82 which leads back into the upper portion of the receiving tank 14.

The superheater 23 itself consists of a number of sections of pipe. In the diagram the number of sections is reduced and they are marked 23^a. Pipe lengths are joined in lateral pairs at opposite ends by means of return bends 23^b. The ends of the pipes are flanged and the return bends are 85 also flanged. The chamber within which the pipes are housed is closed at opposite ends by doors 25 and 26. A more elaborate description and illustration of the detail structure of my preferred retort appears in 90 my copending application Serial No. 69,500 filed December 30, 1915.

On the outlet side of the retort I provide a bend 31, and a pipe 32 leading to the pre-cooler 33, provided with water jacket having 95 inlet and outlet pipes. The valve 35 is shown as a globe valve by means of which pressure in pipe 32 may be held back or reduced before passing into the pipe 36. The pre-cooler has for its principal function to 100 protect the valve 35 from the intense heat of the still 23, communicated through the pipe 32, which not only tends to deposit and burn on the carbon uncracked, but also to destroy the valve or render its operation impossible. 105

At 39 is shown a fractionator or selective condenser consisting essentially of a cylindrical tank or large drum provided to a predetermined height with a material such as steel shavings, or some other refractory mass 110

2
or structure presenting a very large surface and very numerous interstices. The tank is surrounded by a water jacket 39^a having an inlet pipe fitted with a valve 39^v, and a plurality of outlet pipes fitted with valves 39^b and 39^c, the same being located at different points so that the water in the jacket 39^a may be drained off accordingly, whereby effective condensation may be produced to varying degrees. The pipe 36 from the pre-cooler is on a downward slant, and at this end is fitted with an elbow which connects it to a vertical pipe 37 passing horizontally into the tank 39 at the point 38 near its bottom. Leading out from the bottom of the tank is a discharge pipe 40 connected by flange union 41 to a pipe 42 leading to the inlet 43 of the telltale 44 whose outlet 45 is connected through a T-joint 46 and valve 47 to the return pipe 48. This pipe extends as shown to the primary vaporizer or boiler 1, and is the return charge pipe to which reference has heretofore been made. Liquid separated out in the fractionator 25 passes down through the pipe 40 into the telltale which is fitted with a plurality of try-cocks 44^a, 44^b and 44^c or equivalent indicating means. At convenient intervals the valve 47 is opened enough to blow out the contents of 30 the telltale through 48 and so back to the primary condenser for renewed treatment for pressure equalization and for any dense hydrocarbon which rises above the packing of the fractionator, an overflow pipe 49 is 35 provided extending through a T-joint 50 and a trap 52 to the horizontal section 53 and the T-joint 46 of the telltale drain pipe. The trap 52 is arranged so it can be cleaned at intervals by disconnecting the flange union 40 which unites it to both pipes 49 and 53. The T-joint 50 carries a pressure gage 51.

From the top of the fractionator 39 a vertical pipe 54 ascends to an elbow which connects it to an inclined pipe line 55 running to the final condenser inlet 56.

The condenser consists essentially of lengths of pipe 57 connected by return bends of any desired and usual construction, cooled by circulating water in a tank 70 through 50 the inlet pipe 72 and outlet 71, as determined by the valve 73. The discharge end of the condenser is connected through a flange union 59 and pipe 60 to an inlet on the receiving tank or drum 61 which is fitted 55 with a liquid gage 61^c having valve 61^a and 61^b. From the drum 61 the gas pipe 62 extends to a flange union 63 by which it is connected to the return pipe 65, through a valve 64. The pipe 65 extends to the furnace 60 2, where it terminates in the nozzle 67 controlled by the valve 66. Assuming the valve 64 to be open, the nozzle 67 will supply the non-condensing gases from the tank or receiving drum 61 to the furnace 2, thus utilizing what would otherwise be wasted. It

must be understood, however, that I am not limited to this supply of gas for fuel in the furnace 2, but in raising the efficiency of the apparatus, I find it desirable to burn these gases which make a very hot and efficient 70 flame.

The refined product of characteristics determined by selective action of the fractionator, is drawn off from the receiving drum 61 through drainage pipe 68 controlled by the valve 69. In addition to this product, there may be others separated out and drained off as described in my prior applications for example No. 32,704, filed June 7, 1915; but in the present case, a run may be 80 made on the one desired product and all rejected or separated constituents sent back through the return pipe 48 to be redistilled and re-cracked.

With the foregoing apparatus my method 85 of operation is as follows:

The primary vaporizer is supplied with a suitable charge of the hydrocarbon to be cracked and heat applied by means of the burner 67. As the hydrocarbon is vaporized 90 the vapors pass off through the pipe 11 into the condenser 12 where they are condensed and drained off in the form of distillate into the receiving tank 14. When the receiving tank is sufficiently charged to begin operation of the pump, the cracking retort 23 is fired and the pump set into operation to draw the distillate from the tank 14 through the pipe 15 and discharge it through the conduits 17 and 20 into and through the retort 100 23. The pressure valve 35 and safety valve 81 maintain the pressure at a constant value, the value being determined according to the set of the valves and indicated by the pressure gage 18. Thus the contents of the 105 cracking retort is brought to the required degree of pressure and of temperature, the latter being attained by regulating the supply of fuel through the valve 30 or the equivalent. As the heated distillate passes through the pipe 23^x of the retort, it is cracked, forming new chemical series. These products pass along through the pre-cooler 33 and through the pressure controlling or reducing valve 35 to the fractionator 39 which acts to condense and pass off through the telltale those constituents having a specific gravity which prevents their going over to the condenser. The lighter products, however, climb over the 110 bend in the pipe 54, pass through the pipe 55 to the final condenser 57, are cooled therein and thence through the pipe 60 into the receiving tank or drum 61, carrying with them non-condensable gases which as heretofore stated are drawn off through the pipes 62-65; while the liquid hydrocarbon product is drained off through the pipe 68 and valve 69.

If, during operation, the pressure in the 115

cracking retort and consequently in conduits 17 and 20 should rise beyond the pressure point to which the valve 81 is set, this valve will operate to relieve the pressure by allowing some of the liquid hydrocarbon to discharge back into the receiving tank 14. The receiving tank may be provided with any suitable means for venting, or relieving excessive pressure or partial vacuum, as well

10 understood in the art.

Thus, in accordance with the present invention, the hydrocarbon is refined by first distilling then condensing and then cracking in totality and in the liquid phase.

15 In practising this invention, it should be noted, as fully described in my copending application Serial No. 69,500, to which reference is hereinbefore made, that the temperatures and pressures employed are of a

20 high order, the former preferably in excess of 400° C., and the latter preferably not less than 100 pounds per square inch. As set forth in Bulletin No. 114 of the Interior Department, Petroleum Technology, page 89,

25 temperatures of 500° to 550° and pressures of 100 pounds and upward, are suitable for the production of gasolene, especially when cracking is carried on in the vapor phase.

I have found high pressure and high temperatures equally effective when cracking in the liquid phase, and in the present case it should be especially noted that I crack in totality, and this idea is to be regarded as an

30 essential feature of the invention. No pro-

vision is made for vaporizing the oil as it 35 enters the cracking coil, and none is desired, but on the contrary the pressure should be so regulated with respect to the temperature that the oil is maintained in the liquid state even though some vapor 40 globules be formed and distributed in its stream as it progresses through the cracking coil. All the conditions and facts above stated, as well as the mechanical details, dimensions, etc., necessary to maintain pressure to the point of liquefaction, are well 45 understood by those skilled in the art and I do not claim the same as within the scope of my invention.

Having thus described my invention what 50 I claim and desire to secure by Letters Patent is—

The process of refining oil which consists in first distilling all the oil at low or atmospheric pressure, retaining all products 55 of distillation without separate condensation, then condensing all condensable products, then placing the entire liquid so condensed in totality and without separation of any fraction, under high pressure and high 60 temperature so as to crack in the liquid phase, then separating out the heavier products and returning them to be again distilled and cracked, and finally condensing the light resultant product. 65

In testimony whereof I affix my signature.

FRANK E. WELLMAN.
